UNITED STATES PATENT OFFICE.

SILAS KILBOURN, OF GRAND HAVEN, MICHIGAN.

DESIGN FOR THE ORNAMENTATION OF FISH-PAILS.

SPECIFICATION forming part of Design No. 16,209, dated August 18, 1885.

Application filed June 22, 1885. Term of patent 7 years.

To all whom it may concern:

Be it known that I, SILAS KILBOURN, of Grand Haven, in the county of Ottawa and State of Michigan, have invented and produced 5 a new and original Design for the Ornamentation of Fish-Pails, of which the following is a specification, reference being had to the accompanying drawing, forming a part thereof.

The leading feature of my invention is the 10 ornamentation of fish-pails, the same consisting in the representation of a net or seine extending around the outside of the pail.

In the drawing I have shown a pail, A, having the representation of a net or seine, B, 15 around the same. On one side of the pail is an open space, C, in which is the representation of one or more sailing-vessels, D, as shown, and in one corner of this space is the circular space E, in which is the representation of a

fish or other marine product which the pail is 20 adapted to contain. The pails having the net marked upon them can readily be distinguished from the ordinary pails now in use.

I claim—

1. The design for a fish pail herein shown 25 and described, the same consisting of a pail having upon its outer surface the representation of a net or seine containing the open space C therein.

2. The design for a fish-pail herein shown 30 and described, the same consisting of a pail having upon its outer surface the representation of a net or seine containing the open spaces C and E therein.

SILAS KILBOURN.
